UNITED STATES PATENT OFFICE.

THOMAS E. GAHAN, OF TOLEDO, OHIO.

PATTERN-PERFORATING MACHINE.

1,244,595.

Specification of Letters Patent.

Patented Oct. 30, 1917.

Application filed January 8, 1917. Serial No. 141,206.

To all whom it may concern:

Be it known that I, THOMAS E. GAHAN, a citizen of the United States, and a resident of Toledo, in the county of Lucas and State 5 of Ohio, have invented a certain new and useful Pattern-Perforating Machine; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 This invention relates to perforating machines, and particularly to those adapted for perforating master pattern sheets.

The object of my invention is the provision of an improved electrically operated 20 machine of the character described, which is simple and inexpensive in its construction and easily operated to perforate sheets of paper or the like in a rapid and efficient manner. Further objects and advantages of 25 the invention will be apparent from the following detailed description thereof.

While the invention, in its broader aspect, is capable of embodiment in numerous forms, a preferred embodiment thereof is illustrated 30 in the accompanying drawings, in which—

Figure 1 is a side elevation of a machine embodying the invention, with a part broken away and with a pattern sheet in operative position therein. Figs. 2 and 3 are different 35 enlarged views of the sheet operated electric circuit interrupting means, with portions of the latter in section. Fig. 4 is a top plan view of the machine. Fig. 5 is an enlarged perspective fragmentary view of the sheet 40 perforating means, and Fig. 6 is a sectional fragmentary elevation thereof.

Referring to the drawings, 1 designates a frame, in the present instance, of elongated 45 triangular form, which is provided at its corners with ball casters 2 to permit a free movement of the frame over a smooth surface, such as the top of a bench, table or the like. The forward or apex end of the frame 1 is provided on its top with a platform 3.

50 Arms 4, 4 project forward in converging relation from the rear end of the frame 1 in substantially parallel superimposed relation thereto, providing a narrow space 5 therebetween to permit a pattern sheet A to be 55 freely inserted therein. The forward ends of the arms 4, 4 are rigidly connected by a

block or bar 6 having an aperture for a perforating pin or punch 7, which, when depressed, coacts with a die-block 8, carried by the frame 1, to perforate an interposed sheet 60 A. The sheet is yieldingly held to the under side of the block 6 at the point of perforating by a spring finger 9 carried by the block 8. The upper end of the pin 7 is headed and a coiled compression spring 10 is 65 disposed between it and the block 6 to retain the pin normally elevated. A lever 11 is pivoted at 12 between the forward end portions of the arms 4, 4 above the block 6 and has its short arm coacting with the top of 70 the pin 7 and its long arm extending rearward and connected by a link 13 to the lower end of the armature or pole piece 14 of an electro-magnet 15 of the solenoid type. The electro-magnet coil is carried by a frame 16 75 rising from the arms 4, 4. It is evident that an energizing of the electro-magnet will rock the lever 11 and effect a depression of the perforating pin 7.

A pair of arms 17, 17 are rigidly fixed at 80 their rear ends, in the present instance, to the rear ends of the respective arms 4, 4 and extend forward on an incline and in converging relation with their free ends secured together over the platform 3 in vertically 85 spaced relation thereto. The arms 17, 17 may be referred to as a forked arm or super-frame.

A disk 18 of insulating material is carried by the arms 17, 17 at their under sides over 90 the platform 3 and has a marginal electrical conductive ring 19 on its top surface, with a terminal post 20 rising therefrom.

A vertical spindle 21 is journaled in the arms 17, 17 axially of the disk 18 and carries a turn-table 22 of insulating material 95 below said disk in spaced relation thereto. An electrical conductive ring 23 is mounted on the top marginal edge portion of the table 22, and with it an electric brush 24 has 100 yielding wiping contact. This brush is carried by a terminal post 25, which projects up through the disk 18 free from contact with the ring 19 and is insulatingly fixed to a side of the arm 17.

105 A caster-wheel carrying fork 26 depends on an incline from the bottom of the table 22 centrally thereof and carries, what may be termed, a commutator-wheel 27, which rests on the platform 3 or on a sheet A disposed therebetween, and is intended to be 110 rotated by the movement of a pattern

sheet over the platform 3. A coiled compression spring 28 encircles the spindle 21 between the arm 17 and table 22 and causes the wheel to have a yielding downward pressure against a pattern sheet with which it coacts. The wheel 27 has a plurality of equidistantly spaced radial electrical conductor strips 29 having insulation 30 therebetween and electrically connected at their inner ends in the manner of a commutator ring. The strips 29 have their inner ends in electrical connection with the ring 19 through the wheel spindle, fork 26 and an electric brush 31, which projects from one side of said fork around the edges of the table 22 and disk 18 with its free end in yielding wiping contact with the ring 19 (Fig. 3).

A small wheel 32 serving as an electric brush member is carried by a rocker arm 33 in yielding contact with a side of the wheel 27 so that upon a turning of the wheel 27 on its axis the wheel 32 will have alternate contact with the conductor strips 29 and insulation 30. The contact wheel 32 is in electrical connection with the ring 23 through the arm 33, shaft 34 carrying the same, shaft bearing 35 and bolts or rivets 36, which bolts or rivets secure the bearing 35 to the under side of the table 22 and have contact at their upper ends with the ring 23. A coiled contractile spring 37 connects an arm 38 of the shaft 34 to the table 22 and serves to hold the wheel 32 in yielding contact with the commutator wheel.

In the wiring illustrated, 39 designates one side of the line which is connected to the post 20, and 40 the other side of the line which is connected to the post 25 and has a control switch 41, the coil of the electromagnet 15, and a circuit breaking means disposed therein. The circuit breaking means is automatically operated to break the circuit at each upward movement of the rear end of the perforating lever 11 and is for the purpose of causing a more rapid making and breaking of the circuit than would be possible if the commutator wheel 27 was alone depended on for such purpose and also for the purpose of preventing an injurious arcing from occurring between the wheels 27 and 32 as the contact between the latter and the strips 29 of the former is broken.

The circuit breaking means which I have illustrated comprises a rocker arm 42, which is pivoted for vertical rocking movements in a stud 43 projecting from an insulating board 44, which is carried by a standard 45 rising from one end of the arms 4. The arm 42 carries a carbon 46, which coacts with a subjacent carbon 47 to limit the downward rocking movement of the arm, the carbon 47 being adjustably carried by a bracket 48. The circuit wire 40 is split and

has one end connected to the rocker arm 42 by a binding screw 49 and has an end connected to the bracket 48 by a binding screw 50. It is thus evident that when the carbons 46 and 47 are in contact the current 70 is permitted to flow through the line, and the circuit is broken by a separating of the carbons. A spring finger 51 is fixed at one end to the board 44 and acts at its other end against the rocker arm 42 to resist an 75 upward or circuit breaking movement thereof. A finger 52 is adjustably carried by the long arm of the lever 11 and projects upward therefrom in position to adapt it, when raised a predetermined extent by a 80 rocking of the lever, to engage an insulating block 53, adjustably carried by the rocker arm 42, and effect a raising of the rocker arm to separate the carbons 46 and 47 and break the circuit. It is evident that during 85 the period of contact of the contact wheel 32 with a contact strip 29 of the commutator wheel the lever 11 is caused to have a rapid vibratory movement due to the breaking of the circuit at each upward movement of the rear end of the lever and the closing of such circuit at each downward movement of such end of the lever.

In the use of my machine the sheet A to be perforated is anchored at its ends or in some other suitable manner against movement and the machine is moved over the sheet as the perforating of the same may require. To facilitate such movement the machine is mounted on the casters 2 to permit a free movement of the same over the bench, table or other support, and the rear end of the machine is provided with a handle 54 to be grasped by one hand of the operator, said handle, in the present instance, comprising a bolt which connects the sides of the frame 1 at their rear ends, while the other hand of the operator is intended to grasp a handle 55, which extends transversely from the forward end of the 100 superframe or fork 17.

In the operation of my machine an operator places a sheet A in the space 5 between the frame 1 and arms 4 and between the platform 3 and commutator wheel 27, with the perforating pin 7 disposed at the point where it is desired to commence the perforating of the sheet. The operator then closes the switch 41 and moves the machine with respect to the sheet A so that the perforating pin 7 is caused to follow the line to be perforated. The movement of the machine in whatever direction with respect to the sheet will cause the commutator wheel 23 to rotate so as to successively make and break the electric circuit by reason of the conductor strips 29 of the wheel successively moving into contact with the contact wheel 32. The closing of the circuit in this manner causes an energizing of the electro-mag- 110 115 120 125 130

net 15 and a consequent movement of the lever 11 to impart a perforating movement to the pin 7. Upon a raising of the rear end of the lever 11 the finger 52 thereof strikes the insulated lug 53 and raises the rocker arm 42 to separate the carbons 46, 47 and break the circuit, thus permitting the lever 11 to return to its normal position and the carbons 46 and 47 to again make contact to energize the electro-magnet and again impart a perforating movement to the lever 11 and a consequent separating of the carbons to again break the circuit, this being repeated as long as the wheel 32 and a strip 29 of the commutator wheel remain in contact. It is evident that the wheel 27 always has a trailing action with respect to the direction of movement of the machine, the table 22 turning with the orbital movements of the wheel. The brushes 24 and 31 remain in permanent contact with the respective rings 23 and 19 during a turning of the table so that the circuit is not broken by reason of such turning.

25 It is evident that I have provided a simple and efficient perforating machine, which is capable of being easily operated to effect a rapid perforating of a master pattern sheet and that the rapidity of movement of the perforating pin does not depend entirely on the speed of turning of the commutator wheel 27.

30 I wish it understood that my invention is not limited to any specific construction, arrangement or form of the parts, except in so far as such limitations are specified in the claims.

35 Having thus described my invention, what I claim as new, and desire to secure by Letters Patent, is—

40 1. In a machine of the class described, a perforating means, an electric circuit, an electro-magnet disposed in said circuit for actuating said means, and means including a brush member and a wheel with which it engages and operable to make and break said circuit when the wheel is rotated, said wheel being in engagement with a sheet being perforated and rotated by relative movements of the sheet and the wheel axis.

45 2. In a machine of the class described, a sheet perforating means, an electric circuit, an electro-magnet disposed in said circuit, and adapted when energized to actuate said means, and means disposed in said circuit and having a commutator-wheel in engagement with a sheet being perforated and rotated thereby and having a member separate from the sheet and coacting with said wheel to successively make and break the circuit when the wheel is rotated.

50 3. A machine of the class described having a platform over which a sheet to be perforated may be moved, sheet perforating means, an electric circuit, an electro-magnet

disposed in said circuit and adapted when energized to operate said means, and means separate from the sheet being perforated and operated by relative movements of the sheet and platform to successively make and break said circuit.

55 4. In a machine of the class described, a frame having a platform over which a sheet to be perforated may be moved, sheet perforating means having an operating lever, and electrical means having connection with said lever and operable to vibrate the lever upon a making and breaking of an electric circuit, said electrical means being independent of the sheet and having a control part in engagement with the sheet in opposition to said platform and movable to successively make and break the operating circuit when the sheet and platform are relatively moved.

60 5. In a machine of the class described, sheet perforating means having an electro-magnet control, and means in circuit with said electro-magnet and having a rotatable circuit making and breaking part movable by relative movements of a sheet being perforated and the machine, and a brush member in coaction with said part, said last means being operable to successively make and break the electro-magnet circuit when said part is rotated.

65 6. In a machine of the class described, sheet perforating means having an electro-magnet control, means in circuit with the electro-magnet and having a commutator part in rolling contact with a sheet being perforated and a brush member in contact with said part, said last means being operable by relative movements of the sheet and machine to successively make and break the electro-magnet circuit.

70 7. In a machine of the class described, a wheel, means carrying said wheel for pivotal trailing movements in rolling contact with a sheet being operated on and in a plane normal thereto, means forming an electric circuit and coacting with said wheel to successively make and break such circuit when the wheel is rotated, and means having a part in said circuit and operable by an opening and closing thereof to perforate a sheet with which said wheel has contact.

75 8. In a machine of the class described, an electric circuit, an electro-magnet in said circuit, sheet perforating means operated by said electro-magnet upon an opening and closing of said circuit, and means having a revoluble trailing commutator wheel and a brush member in contact therewith, said wheel being in rolling contact with a sheet being perforated and operable to successively open and close said circuit by a relative movement of the sheet and machine.

80 9. In a machine of the class described, an electric circuit, electrically operated sheet perforating means having a part disposed in

21
said circuit and operable by an opening and closing of the circuit, a commutator wheel, means carrying said wheel for rotary and revoluble movements with the wheel in rolling contact with a sheet being perforated, said commutator wheel having its conductor strips in permanent connection with one side of the circuit, and means in permanent connection with the other side of the circuit and coacting with said wheel to successively open and close the circuit when the wheel is rotated.

10. In a machine of the class described, an electric circuit, sheet perforating means having an electrical operating part in said circuit and operated by an opening and closing of the circuit, means disposed in said circuit and operable by a relative movement of the sheet being perforated to effect a successive opening and closing of said circuit, and auxiliary circuit opening and closing means operated by said perforating means.

11. In a machine of the class described, sheet perforating means having a lever, an electric circuit, means operated by an opening and closing of said circuit to vibrate said lever to operate the perforating means, means normally closing said circuit and operated by predetermined movements of said lever to open said circuit, and means disposed in said circuit and operable by movements of a sheet in contact therewith while being perforated to effect a successive opening and closing of said circuit.

12. In a machine of the class described, a perforating means, an electric circuit, an electro-magnet disposed in said circuit for actuating said means, mechanical means having coaction with and operated by the movement of a sheet being perforated to effect

successive making and breaking of the electro-magnet circuit, and auxiliary circuit breaker means actuated by movements of said perforating means to repeatedly break 45 said circuit.

13. In a machine of the class described, an electric circuit, a sheet perforating means, an electro-magnet in said circuit, and separate means for making and breaking said 50 circuit, one of said means being operated by said perforating means and the other being operated by relative movements of the machine and the sheet being perforated.

14. In a machine of the class described, 55 an electric circuit, an electro-magnet in said circuit, a sheet perforating means actuated by said magnet, and separate means for making and breaking said circuit, one being actuated by an operating of said perforating means and the other having a rolling part in contact with a sheet being perforated and operated by turning movements of such part.

15. In a machine of the class described, 60 an electric circuit, sheet perforating means having an actuating electro-magnet in said circuit, and separate circuit breaker means, one of said means normally standing in one position of its movement and automatically 70 movable from such position by perforating movements of said perforating means whereby a circuit is repeatedly opened and closed, and the other of said circuit breaker means having a part in contact with a sheet being 75 perforated and movable to repeatedly make and break a circuit by relative movements of the machine and sheet.

In testimony whereof, I have hereunto signed my name to this specification.

THOMAS E. GAHAN.
